GAME BOARD

Paul G. Lowell, Fort Hill, Biddeford, Maine

Filed July 29, 1963, Ser. No. 76,021

Term of patent 3½ years

(Cl. D34—5)

FIG. 2.

The dominant features of my design reside in the portions shown in the drawings in full lines.

I claim:

The ornamental design for a game board, as shown and described.
